UNITED STATES PATENT OFFICE.

ROBERT A. ILG, OF CHICAGO, ILLINOIS.

STARTING-BOX.

1,282,842.

Specification of Letters Patent. Patented Oct. 29, 1918.

Application filed July 22, 1916. Serial No. 110,659.

To all whom it may concern:

Be it known that I, ROBERT A. ILG, a citizen of the United States, residing at Chicago, in the county of Cook and State of Illinois, have invented certain new and useful Improvements in Starting-Boxes, of which the following is a specification.

This invention relates in general to the starting box for starting and controlling electric motors and has more particular reference to the relation between the starting arm and the release member and to the manner of manipulating these elements.

In starting boxes employed prior to my present invention the starting arm has been equipped with a handle by means of which the arm is moved in starting the motor across a series of contact terminals to successively cut in or cut out a series of resistance units, and the release member is arranged to be moved by the starting arm into engagement with the release magnet only when the starting arm has reached the extreme limit of its starting movement so that the motor is then traveling at maximum speed. Should it be desirable in starting boxes of this character to slow down the motor the starting arm must then be moved backwardly across the contact terminals until the required resistance is cut into the circuit of the motor to give the desired speed. Irrespective of what motor speed may be desired it is necessary, in order to bring the release arm into engagement with the release magnet, to swing the starting arm into full speed position thereby producing a motor speed which may be greater than is necessary or desirable. The above discussion refers particularly to series motors.

One of the primary objects of my present invention is to so construct and arrange the starting arm and release member that the operator, instead of moving the release member into engagement with its magnet by means of the starting arm, moves the release member directly into engagement with its magnet without touching the starting arm, a connection being provided which, when the release member approaches the magnet, automatically moves the starting arm from inoperative position into circuit-closing contact with the first contact terminal of the starting resistance. The starting arm may thereafter be swung independently of the release member across the starting resistance

contacts until the desired motor speed has been attained so that the motor is gradually brought up to the desired speed without speeding it up to its maximum and then subsequently retarding it to the desired speed. 60

Another object of my invention is to provide a guard for the handle of the starting arm which will prevent the operator from moving the starting arm until the release member has first been moved into engagement with its magnet. 65

Other objects and many of the inherent advantages of my invention will be readily appreciated as the same becomes better understood by reference to the following description when considered in connection with the accompanying drawings. Referring to the drawings,

Figure 1 is a plan view of a starting box equipped with my invention; 75

Fig. 2 is a sectional view on the line 2—2 of Fig. 1;

Fig. 3 is a fragmentary sectional view on the line 3—3 of Fig. 1; and

Fig. 4 is a fragmentary sectional view on the line 4—4 of Fig. 4.

On the drawings reference character 5 indicates generally a starting box consisting of a frame in which the starting resistance coils (not shown) are mounted in the usual manner, which frame is provided with the usual top plate 6 made of insulating material. Upon the face of this plate is mounted a series of resistance contact terminals 7 connected with the resistance coils beneath the plate in the usual manner, the resistance being shown diagrammatically, as indicated by reference character 8, and at the maximum speed end of the series of contact terminals 7 there is mounted the usual release magnet 9, 85 preferably connected, as shown in the present instance, in series with the starting resistance. 90

Upon an upright pivot pin 11 carried by a suitable base 12 there are pivotally mounted the starting arm 13 and the release member 14, the release member being attached to a yoke 15 which pivotally engages the pin 11. A coil spring 16 having one end 17 anchored in a socket in the base 12 and its other end 100 engaged with the yoke 15 normally swings the release member in a counterclockwise direction, viewing Fig. 1, against the starting arm 13 and holds this arm through the intermediary of the release member against the 105

stop 19 in which position the contact portion 21 of the starting arm is engaged with a blank contact member 22 so that the current is shut off.

- 5 The release member 14, as will be apparent from Fig. 1, extends outwardly beyond the starting arm and is equipped at its outer end with an operating handle or knob 23. The starting arm is also equipped with a 10 shorter handle or knob 24 which, when the parts are in the position shown in Figs. 1 and 3, is covered by a guard 25 extending laterally from the release member over the knob or handle. This guard is designed to 15 prevent the operator from grasping the knob 24 and swinging the starting arm and the release member together across the contact terminals to bring the release member into engagement with its release magnet 9, as 20 has been the practice heretofore. Instead, an operator starting a motor with a starting box constructed in accordance with my present invention, grasps the handle 23 of the release member and swings this member 25 from the position shown in full lines in Fig. 1 to that shown in dotted lines wherein the member is in engagement with the core of the release magnet 9 by which it is held in this dotted line position so long as 30 current passes through the windings of the magnet. The yoke 15 is provided with a finger 26 which is brought into engagement with the starting arm just before the release member comes in contact with the magnet 35 so that upon final swinging movement of the release member the starting arm is moved by this finger from the blank contact 22 onto the first starting resistance contact 7 as shown by the dotted line position of the 40 starting arm in Fig. 1. Since the circuit is closed by engagement of the starting arm with the first resistance contact just before the release member engages with its magnet, it will be obvious that the magnet will be 45 energized to retain the release member in the position shown in dotted lines in Fig. 1. The motor is now traveling at its lowest speed and the operator can increase this speed to any desired amount by grasping 50 the handle 24 and moving the starting arm across the resistance contacts 7 until the desired speed of the motor has been attained. The parts will then remain in the position to which they have been set and the motor will 55 continue to run until the current is discontinued, whereupon the magnet will release the member 14 and the spring 16 will swing the member 14, and thereby the starting arm, into the inoperative position shown in 60 full lines in Fig. 1.

It will thus be obvious that the release member is held by the magnet as soon as the starting arm is moved onto the first resistance contact and that the starting arm 65 may then be gradually moved up to give the

desired motor speed without moving it to full speed position as has heretofore been necessary for the purpose of setting the release member. The speed of the motor may therefore be gradually increased without at 70 any time exceeding the desired speed, and should the current be cut off the starting arm will be immediately returned by the release member to neutral position from any point at which it has been set. 75

It is believed that the principle of my invention and the construction of one preferred embodiment thereof will be understood from the foregoing without further description, but it should be obvious that the 80 structural details can be varied within considerable limits without departing from the essence of the invention as defined in the following claims.

I claim:

1. In a starting box, the combination of a pivoted starting arm provided with a handle, a release magnet, a release arm pivoted concentrically with said starting arm and disposed between the latter and said magnet, a handle on said release arm, means connected with said release arm for moving said starting arm into low speed circuit-closing position during the latter part of the movement of said release arm toward 95 said magnet, and a spring acting on said release arm to move the latter, and thereby said starting arm, into inoperative position when said release arm is released by said magnet. 100

2. In a starting box, the combination of a starting arm provided with a handle, a release member provided with a guard overlying said handle when the parts are in inoperative position, a release magnet, means 105 connected with said member for moving said arm into circuit-closing position when said member is manually moved into coöperative relation with said magnet, and a spring acting on said release member to 110 move said member, and thereby said starting arm, into inoperative position when said member is released by the magnet.

3. In a starting box, the combination of a starting arm provided with a handle, a release member pivoted concentrically with said starting arm and provided with a guard overlying said handle when said arm and member are in contiguous relation with each other, a release magnet, a handle by which 120 said release member may be swung into engagement with said magnet, and a finger connected to said member in position to engage said arm and move the same into circuit-closing position when said member is 125 engaged with the magnet.

4. In a starting box, the combination of a series of starting resistance units, a pivoted starting arm provided with a handle, a release magnet, a release arm pivoted con- 130

trically with and lying alongside of said starting arm between the latter and said magnet in the inoperative position of said starting arm, a handle on said release arm, 5 a spring normally urging said release arm sidewise against said starting arm, and means carried by said release arm serving

to engage said starting arm and move the latter into contact with the first of said resistance units during the final part of the 10 swinging movement of said release arm toward said magnet.
